UNITED STATES PATENT OFFICE.

HIRAM V. GORRELL AND JOHN B. GORRELL, OF KENDALLVILLE, INDIANA.

HEAT-RADIATOR.

1,039,927.

Specification of Letters Patent.

Patented Oct. 1, 1912.

Application filed December 11, 1911. Serial No. 665,180.

To all whom it may concern:

Be it known that we, HIRAM V. GORRELL and JOHN B. GORRELL, citizens of the United States, residing at Kendallville, in the 5 county of Noble and State of Indiana, have invented certain new and useful Improvements in Heat-Radiators; and we do declare the following to be a full, clear, and exact description of the invention, such as will 10 enable others skilled in the art to which it appertains to make and use the same.

This invention relates to improvements in heat radiators.

The object of the invention is to generally 15 improve the construction and operation of the several parts of a radiator and with this object in view, the invention consists in the improved construction, arrangement and combination of parts hereinafter fully de- 20 scribed and afterward specifically claimed.

In the accompanying drawings; Figure 1 is a perspective view of our improved radiator; Fig. 2 is a central vertical longitudinal section thereof; Fig. 3 is a horizontal sec- 25 tion; Fig. 4 is a vertical cross section on the line 4—4 of Fig. 2; Fig. 5 is a similar view on the line 5—5 of Fig. 2.

Referring more particularly to the drawings, 1 denotes the outer shell or casing of 30 the radiator which may be of any suitable shape and which is here shown as having its side walls formed in a series of convolutions and having its ends rounded. In the bottom of the radiator is formed a series of 35 threaded openings 2 which align with a similar series of smooth openings 3 formed in the top of the radiator. The side walls of the radiator between each of the convolutions are connected together by integrally 40 formed bracing webs or bars 4 whereby the side walls are strengthened to receive the pressure of the steam or hot water with which the radiator is supplied.

Arranged in the radiator is a series of 45 vertically disposed heat radiating and air circulating pipes 5 the lower ends of which are threaded and adapted to be screwed into the threaded openings 2 in the bottom of the radiator while the upper ends project 50 through and extend a suitable distance above the openings 3 in the top of the radiator. The projecting upper ends of the pipes 5 are externally threaded, and adapted to be screwed thereon and into engagement with the top of the radiator are collars 6. The lower edges of the collars 6 are flared out-

wardly to form, between the inner walls of said edges and the adjacent sides of the pipes and top of the radiator a space substantially triangular shaped in cross section 60 in which is arranged a similarly shaped packing ring 7. By thus arranging the packing ring the same will be clamped down into tight engagement with the top of the radiator and adjacent sides of the pipes when 65 the collars 6 are screwed downwardly, thus forming a fluid tight connection between the upper ends of the pipes and the openings in the top of the radiator through which the upper ends of the pipes pass. 70

In the ends of the radiator casing at suitable distances above the bottom thereof are threaded steam or water inlet passages 8 with one or the other of which is connected a steam or water supply pipe 9. The inlet 75 passage opposite to the passage with which the inlet pipe is connected is closed by a plug 8^a. In the ends of the casing below the inlet openings and in line with the bottom of the radiator are steam or water dis- 80 charge passages 10 with one or the other of which is connected a discharge pipe 11, said pipe being arranged at the opposite end of the radiator from that to which the inlet pipe 9 is connected. The discharge passage 85 opposite to that with which the discharge pipe is connected is closed by a plug 10^a. By thus arranging the inlet and discharge passages the steam or water inlet pipe may be connected with either end of the radiator 90 casing and by arranging the inlet passages above the bottom of the casing, steam may enter the casing without passing through or coming into contact with any water of condensation which may have settled in the 95 bottom of the casing.

The radiator is supported at a suitable elevation above the floor or surface on which it rests by feet 12 having in their upper ends recesses or notches 13 adapted to receive attaching lugs or flanges 14 formed on the lower edges of the sides of the radiator as shown. The legs are braced and securely fastened together and into engagement with the lugs 14 by tie rods or bolts 15 arranged 100 beneath the radiator and having their ends engaged with apertures formed in the legs as shown. In thus supporting the radiator the cool air from the lower portion of the room or compartment passes upwardly 105 through the pipes 5 and is heated and passes out in a heated condition through the upper 110

ends of the pipes and into the room. This heating of the air in the pipes causes the air in the lower portion of the room to be drawn beneath the radiator and up through 5 the pipes thus insuring a circulation and uniform heating of the air in the room.

The provision of a steam inlet and a steam outlet at each end of the radiator is a prime improvement and will save much expense, 10 labor and time in installing heating plants. The radiator is reversible so that either side may face outward into the room. For this reason the radiator may be connected up with a line of piping of the height of either 15 inlet and outlet, without raising or lowering either the piping or the radiator. If the piping be too high for the lower inlet and outlet, all that is necessary is to reverse the position of the radiator to bring the upper inlet 20 and outlet into play. Another advantage, especially where the radiator is not reversible is that the piping, by adjusting the plugs may be connected up with either the lower or 25 upper inlet and outlet. Another advantage is that by closing both openings at one end, the two openings at the other end may serve as an inlet and an outlet.

From the foregoing description taken in connection with the accompanying drawings, the construction and operation of the 30 invention will be readily understood without requiring a more extended explanation.

Various changes in the form, proportion

and the minor details of construction may be resorted to without departing from the principle or sacrificing any of the advantages of 35 the invention as claimed.

Having thus described our invention, what we claim is;

A radiator comprising an elongated chamber having side walls, opposite outwardly rounded end walls connecting said side walls and top and bottom walls, said side walls being similarly sinuous in horizontal section and the concave and convex portions thereof 40 being respectively opposite one another, transverse braces integral with said side walls and connecting opposite inwardly convex portions thereof, said top and bottom walls having vertically registering openings 45 50 concentric with the spaces bounded by inwardly concave portions of said side walls, open-ended pipes passing through said openings and secured therein means for supplying said chamber with a heating medium 55 and means for discharging the same therefrom.

In testimony whereof we have hereunto set our hands in presence of two subscribing witnesses.

HIRAM V. GORRELL.
JOHN B. GORRELL.
